UNITED STATES PATENT OFFICE

156,415

FROZEN FOOD STORAGE AND DISPLAY CABINET

Jacob W. P. Fleming, Memphis, Tenn.

Application April 15, 1947, Serial No. 138,401

Term of patent 3½ years

(Cl. D80—11)

To all whom it may concern:

Be it known that I, Jacob W. P. Fleming, a citizen of the United States, residing at Memphis, in the county of Shelby, and State of Tennessee, have invented a new, original, and ornamental Design for a Frozen Food Storage and Display Cabinet, of which the following is a specification, reference being had to the accompanying drawing, forming part thereof.

In the drawing, the figure is a perspective view of a frozen food storage and display cabinet, embodying my novel design, the back and opposite end being plain.

I claim:

The ornamental design for a frozen food storage and display cabinet, as shown.

JACOB W. P. FLEMING.
